CAM AND SLIDE MECHANISM

Emil Bommer, Brooklyn, N. Y.

Application January 11, 1932, Serial No. 585,832

2 Claims. (Cl. 74—55)

This invention relates to a door check and closer of the kind inserted in a recess in the floor, the invention being related more particularly to an improved cam mechanism by means of which a door check and closer of the kind specified can be used with either a double or single-acting door and with either a right or left-hand door.

An important object of the invention is the provision of a cam mechanism which, without any changes or adjustment, can be operated either to the right or to the left and either through any given part of a circle or through a full circle of 360°, so as to accommodate the device for use with equal facility with a door mounted to swing either as a single-acting door, a double acting door, a right-hand door, or a left-hand door.

The improved cam mechanism of my invention may be produced, and preferably is produced, as a compact unit, capable as a unitary construction of being inserted in and removed from the check and closer casing; and the device includes as a part thereof the pintle upon which the door is mounted at its lower end, a frame or connector arranged for reciprocation on the pintle, and cams on the pintle which cooperate with rollers on the frame to cause reciprocation of the frame by the rotary movement of the pintle. According to a feature of the invention, the pintle is made so as to provide for vertical adjustment of the door thereon.

The present application in respect of the subject matter claimed herein, though not in respect of the connection between the door attaching bar and pintle, is a continuation in part of my application for patent, Serial No. 444,971, filed April 17, 1930, for a Door check and closer.

With the foregoing and other objects in view, the invention consists of the novel construction, combination and arrangement of parts as herein-after more specifically described, and illustrated in the accompanying drawing, wherein is shown by way of example a single and practical embodiment of the invention as reduced to practice.

In the drawing, wherein like reference characters denote corresponding parts throughout the several views:

Figure 1 represents a fragmentary longitudinal sectional view through a door check and closer embodying the cam mechanism of the present invention, parts of the cam mechanism being shown in section;

Fig. 2 represents a top plan view of the cam mechanism removed from the casing, the frame and cams being shown in the positions they

occupy with respect to each other and to the pintle when the door is closed;

Fig. 3 is a view similar to Fig. 2 but showing the frame and cams in the positions they occupy with respect to each other and to the pintle 60 when the door is moved 180° from closed position;

Fig. 4 is a cross section taken on the line 4—4 of Fig. 2; and

Fig. 5 is a plan view taken on the line 5—5 of 65 Fig. 1.

Referring with more particularity to the accompanying drawing, 10 denotes the rear portion of an elongated casing of the type which is adapted in accordance with the usual practice 70 to be placed in a suitable cut or cavity in the floor construction. In the bottom wall 11 of the casing is provided a circular, threaded opening 12 which is closed and sealed by means of a circular screw plug 13. For receiving the lower end 75 of the pintle 14, upon which the door is supported, a cup-shaped bearing 15 is countersunk in the central inner face of the plug 13; and in axial alignment with the bearing 15, the top wall 16 of the casing is made with an annular 80 vertically extending bearing 17 through which the vertical pintle extends. Opposite the cup-shaped bearing 15, there is rigidly secured to the pintle by a rivet 18 or otherwise a ball-race bearing 19, and suitable anti-friction balls 20 85 are disposed between the bearings 19 and 15, the last-named having for the balls 20 a suitable annular raceway or groove 21. The vertical pintle for the door is thus supported in an anti-friction manner upon the plug 13 which is removably engaged in the bottom wall of the 90 casing.

Arranged upon the pintle 14 for reciprocation backwardly and forwardly thereon is a frame having in general the form of a yoke comprising 95 upper and lower plates 22 and 23 united at their forward ends by a front portion 24. The two plates 22 and 23 are provided with similar lengthwise extending slots 25. The vertical pintle extends transversely through the slots so that the frame or yoke can be moved backwardly and forwardly upon the pintle. Projecting forwardly from the portion 24 of the frame or yoke is an extension 26 which is transversely holed at 27 for the reception of a coupling pin 105 28' whereby to connect the frame or yoke with a cylinder member 28 which is normally urged forward (to effect the closing of the door) by means of a coil spring 29, said cylinder and coil spring being shown herein only fractionally, as 110

these elements constitute no part of the cam mechanism of the present invention, it being sufficient to note here that in practice the frame or yoke is normally urged forwardly into the position shown in Figs. 1 and 2, being coupled with the spring-urged element. It is in place to state here that a full disclosure of the cylinder 28 and coil spring 29 together with all other parts of a complete door check and closer with 10 which the present improvement may be associated, is presented in the patent application above identified.

The lower plate 23 at the opposite sides of the longitudinal slot 25 therein is slidably engaged in 15 suitable annular guides 30 provided for the purpose in the bearing 19, while the upper plate 22 is engaged for sliding movement in similar annular guides 31 produced in an enlargement 32' on the vertical pintle.

20 For effecting longitudinal movement of the frame or yoke by the rotary movement of the vertical pintle, I provide cam devices 32 and 33 upon the pintle and roller devices 34, 35 and 35' upon the frame or yoke, the roller device 25 34 being arranged to cooperate with the cam device 32, while the roller devices 35, 35', being respectively right and left rollers, as shown in Figs. 2 to 4, cooperate with the cam device 33. The cam device 32 is secured by a rivet 36 or 30 equivalent means to the pintle immediately above the top plate 22, and as herein represented the cam device 33, also rigid with the pintle, occupies a position between the top and bottom plates 22 and 23. The roller device 34 is mounted for 35 operation over the top plate 22 by means of a pin 37 which is secured in the front portion 24 of the frame. The right and left rollers 35, 35' are mounted between the top and bottom plates 22 and 23 at the right and left sides of the frame near the rear end thereof, these roller devices being operatively mounted upon pins 38 which connect the said top and bottom plates as clearly shown in Fig. 4. The cam device 32, rigid with the pintle, is essentially a guide cam, shaped to cooperate with the roller 34 so as to 40 maintain the frame or yoke in that position in which the cam 33 will be kept in contact with the rollers 35, 35' for effecting the movement of the frame. In other words, the two cams and three rollers always provide three control points, the roller 34 and one of the two rollers 35, 35' (depending on the direction of the rotation of the pintle) serving as means for guiding the frame while the other of the two rollers 35 or 35' (as the case may be) serves as means for 45 forcing the movement of the frame. Under clockwise movement of the pintle (as viewed for instance in Fig. 2) the cam 33 acting on roller 35 forces movement of the frame rearwardly; and under anti-clockwise movement of the pintle, said cam acting on roller 35' also forces movement of the frame in a rearward direction. By this arrangement of cams and rollers, the pintle can be moved in either direction 50 through a complete circle of 360°.

65 In Fig. 2, I show the parts in the relative positions which they occupy when the door is in closed position, the frame in this case being drawn forwardly so that the rear ends of the slots 25 are in proximity to the rear side of the pintle; and in Fig. 3 I show the parts in the relative positions which they occupy when the door has been opened through an angle of 180° and in this case it will be seen that the forward ends 70 of the slots 25 are in proximity to the forward side of the pintle. It will thus be evident that

the frame is movable backwardly or rearwardly from its initial or at-rest position as shown in Figs. 1 and 2 for a distance substantially equal to the length of the longitudinal slots 25 during the turning of the pintle through 180°. In practice this backward or rearward movement of the frame takes place against the action of the power means or spring. Whenever the pintle is turned beyond 180°, the frame moves forwardly again towards its initial position. Manifestly, a reverse movement of the pintle towards its initial position from any position to which it may have been moved, will result in forward movement of the frame to the initial position illustrated in Figs. 1 and 2. Being movable through a circle of 360°, the cam mechanism of the present invention has a universal character so that it is suitable for use in door check and closer constructions for a single-acting door, a double-acting door, and as well for either a right or left-hand door.

80 The device of the present invention is a simple, compact unitary construction, consisting of the pintle, the reciprocable frame or yoke, the two cams on the pintle and the three roller devices 85 30 on the frame. Upon the removal of the screw-threaded plug 13, this unitary construction can be installed or removed as an entity. The entity device is installed by inserting it through opening 12 in such manner that the pintle is passed 90 through the bearing 17, after which the screw plug 13 is manipulated so as to apply the pintle to the cup-shaped bearing 15 whereupon the plug is screw-threaded in place in the threaded opening 12. In the type of casing illustrated herein, 95 a screw plug 39 is fitted in the top wall 16 and in such position that when this screw plug is removed, there will be an opening 40 with which the openings 41 in the cylinder 28 may be aligned so that the pin 28' can by insertion through the 100 opening 40 be applied to the openings 41 in the cylinder and the opening 27 in the extension whereby to couple the yoke with the cylinder.

105 It is important to note that the cam mechanism of my invention cannot get out of order and that 110 the parts thereof cannot be damaged or injured, regardless of the extent or direction of movement of the pintle and consequently of the door.

115 For mounting the door on the pintle, any suitable or approved bar may be applied to the lower 120 edge of the door in a manner well understood. In the present instance, I show a fragmental bar 42 of a type suitable for attachment to the door, said bar having a lateral head 42' formed with a vertical eye 43 adapted to fit around the 125 top portion of the pintle above the bearing 17. Novel means are provided whereby adjustably to secure the bar 42 (and hence the door supported thereon) to the pintle. This means consists in providing the top portion of the pintle at 130 one side thereof with a vertically extending notch 44 concavely curved at 45. In open communication with the eye 43, the head 42' is cut away to provide a vertical recess 46 that will come 135 opposite the notch 44. For fitting partly in the 140 notch 44 and partly in the recess 46, I provide a wedge or block member 47 one side 48 of which is of a convex form to fit the concavely curved portion 45. The opposite side of the wedge member 47 has a recess 49 shaped to receive the conical inner end 50 of a screw bolt 51 which is threaded through a screw-threaded opening 52 provided in the head 42'. With this simple construction, it will be evident that before tightening the screw bolt 51, the head with the wedge 150

and hence the bar with door thereupon may be accurately adjusted in a vertical direction with respect to the casing 16.

While the invention has been illustrated and described in considerable detail, it is realized that in practice various changes and alterations may be made therein, and further that the invention is capable of embodiment in many different constructions. It has been sought herein to illustrate only such an embodiment as will suffice to exhibit the character of the invention. Reservation is, therefore, made to the right and privilege of changing the form of the details of construction or otherwise altering the arrangement of the parts without departing from the spirit or scope of the invention or the scope of the appended claims.

I claim:—

1. In a door check and closer, a reciprocable connector having arms consisting of spaced parallel plates longitudinally slotted, a rotatable pintle extending transversely through the slots of said plates to provide for the reciprocation of the plates upon the pintle and with the pintle at its opposite sides engageable with the two spaced plates whereby to prevent any lateral displacement of the plates and hence of the connector in any position of the connector, a cam carried by the pintle adjacent the outer face of one plate and operating on a roller at the front of the plate and in the plane of the longitudinal center of the slot, a second cam carried by the pintle between the plates and operating on right and left rollers carried by the arms between the plates and disposed laterally of the slots, said cams having peripheries mutably shaped and so cooperating with the rollers as to cause during each rotation of the pintle a complete reciprocation backwardly and forwardly of the connector in the direction of the length of the slots with a minimum of friction between the pintle and the arms.

2. In a door check and closer which includes a vertical pintle and a horizontal connecting bar associated therewith to provide for the reciprocation of the bar by the rotation of the pintle, flat vertically spaced and longitudinally disposed arms integrally connected with the bar, having slots therein extending in the direction of their length and in which the pintle is engaged for rotation, cams rigidly attached to the pintle, one between the arms whereby to prevent movement of the arms axially of the pintle, and one at the outer face of one arm, said cams being thus attached adjacent their reduced and rounded heel portions and extending and expanding therefrom in the same direction and in horizontal planes to rotate parallel with the planes of the arms, the peripheries of said cams opposite their heel portions being differently shaped and the periphery of one extending well beyond the outline of the periphery of the other, a pair of rollers engaging the periphery of one cam and located adjacent one end of an arm but respectively at opposite sides of the long axes of the slots, a roller engaging the periphery of the other cam at the other end of the arm and having the axial center disposed coplanar with the longitudinal center of the slots, said cams rotating with the pintle and providing both for partial and complete revolution of the pintle in either direction and cooperating with the rollers and mutably shaped with respect to each other and in respect of the long axes of the slots to provide for direct reciprocation of the connector in the direction of the long axes of the slots and without lateral displacement from the rotating pintle the opposite sides of which have engagement with the two vertically spaced arms in all positions of the latter.
